UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 34,240, dated March 19, 1901.

Application filed April 12, 1900. Serial No. 12,640. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawings, forming a part thereof.

In the said drawings, Figure 1 is a plan view of a plate, showing my design. Fig. 2 is a vertical cross-section of the same.

The periphery of the plate is provided with a series of indentations or depressions A, giving an undulating contour. From each one of these depressions a raised radial line B extends to the step or ledge G, dividing the brim into panels D. The step G corresponds in

contour to the periphery and is provided with 20
escallops E, with raised radial lines E' extending downwardly and inwardly and merging in the surface of the plate. From these escallops small acorn-like ornaments F project toward the periphery A of the plate. The 25 panels D are slightly concave, as is also the center of the plate.

What I claim is—

The design for a plate or similar article substantially as herein shown and described. 30

Signed at the city of New York, in the county and State of New York, this 14th day of March, 1900.

CHARLES J. AHRENFELDT.
